UNITED STATES PATENT OFFICE.

FRANK HARRISON WILSON, OF MONTROSE, PENNSYLVANIA.

SEWING OR WORK BASKET HOLDER.

No. 926,798.

Specification of Letters Patent.

Patented July 6, 1909.

Application filed February 6, 1909. Serial No. 476,504.

To all whom it may concern:

Be it known that I, FRANK HARRISON WILSON, a citizen of the United States, residing at Montrose, in the county of Susquehanna and State of Pennsylvania, have invented certain new and useful Improvements in Sewing or Work Basket Holders; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in holders for work, sewing baskets, etc., and consists of a simple and efficient device of this nature which may be conveniently attached to the arm or seat of a chair or other article, and comprises various details of construction, combinations and arrangements of parts which will be hereinafter fully described and then specifically defined in the appended claims.

My invention is illustrated in the accompanying drawings which, with the letters of reference marked thereon, form a part of this application and in which:

Figure 1 is a perspective view showing the device as applied to the seat of a chair. Fig. 2 is a perspective view showing the device as applied to the arm of a chair. Fig. 3 is a detail perspective view of the device detached from the chair.

Reference now being had to the details of the drawings by letter, A designates the work-holding device which is made preferably of a single piece of metal, preferably wire, which is bent upon itself at B and the two strands of the wire bent to form the S-shaped portion, the convolutions of which are adapted to engage over the bottom of a chair or the arm or round thereof, the wire being preferably of a flexible material and adapted to be frictionally held in place. The portion of the device which engages the

chair or other article, preferably is provided with covering E of felt or other suitable material, so that the article upon which it is held will not be marred. At locations, designated by letter F, the wire is bent outwardly at angles forming the two arms G, G, which terminate in curved ends N designed to engage over the edge of a basket as shown.

As the device is made of a flexible material, the wires may be bent to adjust the device so that it will fit different sized baskets and also bent to engage chairs of different sizes and to adapt the holder to be applied to the round of a chair, seat or arm as may be desired.

What I claim to be new is:

1. A work holding device comprising a wire which is bent upon itself at its longitudinal center, the two arms of the wire being thence bent each in S-shape forming means to engage a chair, said arms having straight parallel portions extending beyond the S-shaped loops, each of said parallel portions being bent upwardly at right angles and having its end curved upwardly and rearwardly and terminating in a hook, as shown and described.

2. A work holding device comprising a wire which is bent upon itself at its longitudinal center, the two arms of the wire being thence bent each in S-shape, the longitudinal center of the wire adapted to engage the edge of the seat of a chair, while the upper of the loops formed by the S-shaped portions are designed to receive the arm of a chair, the arms of the wire beyond the loops extending horizontally and diverging, and the ends of the wires being curved upwardly and rearwardly and terminating in hooks, as shown and described.

In testimony whereof I hereunto affix my signature in the presence of two witnesses.

FRANK HARRISON WILSON.
